CLAIM

The ornamental design for a perfume bottle, as shown and described.

DESCRIPTION

FIG. 1 is a front elevational view of a perfume bottle showing my new design;

FIG. 2 is a right-end elevational view thereof;

FIG. 3 is a left-end elevational view thereof;

FIG. 4 is a top-plan view thereof; and

FIG. 5 is a bottom plan view thereof.

The rear of the perfume bottle is a mirror image of the front thereof.

FIG. 1FIG. 2FIG. 3FIG. 4FIG. 5
